(57) **CLAIM**

The ornamental design for a golf club head sole, as shown and described.

DESCRIPTION

FIG. 1 is a sole, heel side perspective view of a new design for a golf club head sole;

FIG. 2 is a heel side view thereof;

FIG. 3 is a toe side view thereof;

FIG. 4 is a back view thereof;

FIG. 5 is a bottom view thereof; and,

FIG. 6 is a front view thereof.

The portion of the club head shown in phantom is for illustrative purposes only and does not form any portion of the claimed design.
